CLAIM

The ornamental design for a mobile phone, as shown and described.

DESCRIPTION

FIG. 1 is a perspective view of a mobile phone showing our new design;

FIG. 2 is a front view thereof, where the rear view is a mirror image;

FIG. 3 is a left side view thereof, where the right side view is a mirror image;

FIG. 4 is a top plan view thereof, where the bottom plan view is a mirror image;

FIG. 5 is a front perspective view thereof, showing an example of the usage of the subject design; and,

FIG. 6 is a rear perspective view thereof showing an example of the usage of the subject design.

The broken lines in FIGS. 5 and 6 that are shown on the claimed surfaces show non-claimed examples of possible displayed subject matter. The additional broken lines shown outside the claimed surfaces show portions of the mobile phone that form no part of the claimed design. The broken lines form no part of the claimed design.
